United States Patent Office.

CHARLES C. PURINGTON AND JAMES PURINGTON, OF BATH, MAINE.

Letters Patent No. 70,118, dated October 22, 1867.

IMPROVED WASHING MACHINE.

The Schedule referred to in these Letters Patent and making part of the same.

TO ALL PERSONS TO WHOM THESE PRESENTS MAY COME:

Be it known that we, CHARLES C. PURINGTON, and JAMES PURINGTON, of Bath, in the county of Sagadahock, and State of Maine, have invented an Improved Washing Machine; and do hereby declare the same to be fully described in the following specification, and represented in the accompanying drawings, of which—

Figure 1 is a top view,

Figure 2 a longitudinal section, and

Figure 3 a transverse section of a washing machine provided with our invention.

In such drawings, A denotes a rectangular tub, provided with a series of rollers, *a a a*, &c., extending transversely across and within it, and arranged with their axes in an inclined plane. A reciprocating dasher, B, is employed, it consisting of a series of rollers, *b b b*, &c., and a frame, *c*, for supporting them, such frame being affixed to another frame composed of two levers *d d*, and three cross-ties *e e*, and *f*, the whole being arranged as represented. The two levers *d d* are jointed to two slide-bars *g g*, each of which is arranged between two parallel guides *h i*. There is a wheel, *k*, applied to the rear part of each slide-bar, and so that the periphery of the said wheel shall bear on the upper edge of the lower of the two rails *h i*. Another such wheel *l* is arranged within each of the upper rails, so that the periphery of such wheel may rest on the upper edge of the slide-bar directly underneath such rail. The slide-bars, the two sets of rails, and the friction-wheels applied to the bars and upper rails, as set forth, serve to steady and guide the dasher during reciprocating movements, which may be imparted to it by laying hold of the rear connection-bar or handle of such dasher, and moving the dasher on its rollers to and fro over the series of rollers of the tub. The above-described means of steadyng and guiding the dasher will enable a person, while moving it as explained, to bear it down with any proper pressure upon the clothes, when between its rollers and those of the tub. The machine thus made, we have found to be very efficient for the purpose for which it is intended.

The operation of washing clothes or other articles with the machine will be readily understood by persons accustomed to the use of washing machines.

We claim the combination as well as the arrangement of the guide-bars *g g*, the two sets of rails, and their wheels, with the tub, its series of rollers, and the dasher and its rollers, the whole being substantially as specified.

CHARLES C. PURINGTON,
JAMES PURINGTON.
